COMBINED ARTIFICIAL FLOWER, POT, AND
PLANT STEM ORNAMENT

George W. Ellison, Baltimore, Md.

Application February 20, 1950, Serial No. 8,036

Term of patent 7 years

(Cl. D29—1)

To all whom it may concern:

Be it known that I, George W. Ellison, a citizen of the United States, residing at Baltimore city, State of Maryland, have invented a new original, and ornamental Design for a Combined Artificial Flower, Pot, and Plant Stem Ornament, of which the following is a specification, reference being had to the accompanying drawings, forming a part hereof.

Fig. 1 is an elevational view of a combined artificial flower pot, and plant stem ornament, showing my new design;

Fig. 2 is an enlarged fragmentary view of a portion of Fig. 1;

Fig. 3 is a sectional view of the pot and stem taken on line 3—3 of Fig. 1; and

Fig. 4 is a sectional view taken through the pot.

I claim:

The ornamental design for a combined arti-

ficial flower, pot, and plant stem ornament, as shown.

GEORGE W. ELLISON.
